ATTORNEY

WITNESS:

UNITED STATES PATENT OFFICE.

BENJAMIN PORTER, OF FULLERTON, NORTH DAKOTA.

HEADLIGHT BULB AND DEFLECTOR.

Application filed February 24, 1926. Serial No. 90,386.

This invention relates to illuminating devices, particularly to headlamps for automobiles, and has for its object the provision of a novel combined bulb and reflector 6 adapted to be used in an ordinary automobile headlamp to replace the usual bulb, the construction and operation being such that the light will be concentrated upon the roadway at the area where it is most desirable 10 while at the same time there will be no blinding glare in the eyes of the drivers of approaching cars.

An important and more specific object is the provision of a device of this character 15 which embodies simply a bulb of simple construction formed with an integral and peculiarly constructed reflector device which acts not only to prevent the light from passing to undesired points or areas but which 20 also concentrates the light at the places where it is most needed.

An additional object is to provide a device of this character which will be simple and inexpensive in manufacture, easy to apply and use, positive in action, efficient and durable in service, and a general improvement in the art.

With the above and other objects and advantages in view, the invention consists in 30 the details of construction and the arrangement and combination of parts to be herein-after more fully described and claimed, and illustrated in the accompanying drawings, in which:

35 Figure 1 is a sectional view taken in a vertical plane through an automobile head-lamp equipped with the invention.

Figure 2 is a cross section taken on the line 2—2 of Figure 1, and

40 Figure 3 is a cross section taken on the line 3—3 of Figure 1.

Referring more particularly to the drawings, the letter A designates the reflector of an ordinary automobile headlamp, at the 45 center of which reflector is mounted the usual type of socket B ordinarily provided for holding the bulb. The headlamp casing and the lens at the front thereof are not illustrated as they form no part of the present invention, and it is likewise clear that the ordinary type of bulb is not shown for the same reason.

In carrying out the invention, I provide 50 a combined bulb and reflector comprising a bulb member 10 which may be of entirely or substantially spherical form and provid-

ed at one end with the usual base 11 adapted to be engaged within the socket B in the usual manner. The bulb is of course provided internally with a filament 12 which 60 becomes incandescent as is well known when current is passed through it.

Formed integrally with the bulb 10 and coaxially with the axis of the base 11 is a deflector comprising a conical shell member 65 13 which may be circular in cross section throughout or circular throughout a portion of its length, as indicated in Figure 2 and which may have its end portion of polygonal or other formation as indicated in Figure 70 3. These details are immaterial and it is quite evident that many variations may be resorted to. The open end of the shell is covered by a lens or pane 14 of glass, celluloid or other transparent or translucent material which may be colored, frosted or otherwise treated in order to avoid glare. It is preferable that the inner surface of the shell be coated as a mirror in order that light passing through the deflecting shell will be intensified. The exterior of the bulb 10 may be frosted or otherwise coated throughout or for only a portion of its extent but that area where the bulb leads into the deflector should of course be left entirely clear so 80 that there will be no obstruction to the rays of light. The bottom portion of the lens or pane 14 is represented as of such construction as to give an opening 15 through which the light may pass with maximum intensity and concentration, there being no glare at this point in view of the fact that it is below the line of vision of the driver of an approaching vehicle.

In the operation of the device, it will be 95 apparent that all the light issuing laterally from the bulb will strike against the reflector A and be deflected forwardly in the usual manner. It is also apparent that the light entering the deflecting member to the 100 point where it communicates or connects with the bulb will pass forwardly in a straight-ahead direction owing to the peculiar shape of the concentrated lens or pane 14. Actual practice and experiment 105 has demonstrated that this device will greatly intensify the light upon the roadway at the area where its use is most desired while at the same time there will be no glare in the eyes of the driver of an approaching car, the device thus operating as a great 110 safeguard to the motoring public in view of

the fact that it lessens the danger of accident. It is believed that the construction, operation and advantages will be readily apparent to one skilled in the art without further explanation.

5 While I have shown and described the preferred embodiment of the invention, it should be understood that I reserve the right to make such changes in the form, 10 construction and arrangement of parts as will not depart from the spirit of the invention or the scope of the subjoined claims.

Having thus described the invention, I claim:—

15 1. A bulb and deflector comprising a bulb having a base adapted to be engaged within a socket, the bulb being provided interiorly with a filament adapted to be heated so as to become incandescent, and a deflector 20 comprising an outwardly flaring substantially conical shell formed integrally upon the bulb diametrically opposite the base thereof and projecting considerably beyond the bulb, the open end of the deflector con- 25 taining a lens.

2. A bulb and deflector comprising a bulb

having a base adapted to be engaged within a socket, the bulb being provided interiorly with a filament adapted to be heated so as to become incandescent, and a deflector comprising an outwardly flaring substantially conical shell formed integrally upon the bulb diametrically opposite the base thereof and projecting considerably beyond the bulb, the open end of the deflector containing a lens, and a lens located at the small end of the deflector.

3. A bulb and deflector comprising a bulb having a base adapted to be engaged within a socket, the bulb being provided interiorly 40 with a filament adapted to be heated so as to become incandescent, and a deflector comprising an outwardly flaring substantially conical shell formed integrally upon the bulb diametrically opposite the base thereof 45 and projecting considerably beyond the bulb, the open end of the deflector containing a lens, a portion of the shell being depressed inwardly.

In testimony whereof I affix my signature.

BENJAMIN PORTER.
